Inventor:

John R. Pearson,
by his attorney,
Charles R. Searle.

UNITED STATES PATENT OFFICE.

JOHN R. PEARSON, OF BROOKLYN, NEW YORK, ASSIGNOR TO HIMSELF, GEORGE W. McCLOSKEY, AND CHARLES Y. VAN DOREN, ALL OF BROOKLYN, NEW YORK.

METALLIC BOX.

1,252,489.

Specification of Letters Patent. Patented Jan. 8, 1918.

Application filed December 29, 1916. Serial No. 139,667.

To all whom it may concern:

Be it known that I, JOHN R. PEARSON, a subject of the King of Sweden, residing in the city of New York, borough of Brooklyn, in the county of Kings and State of New York, have invented a certain new and useful Improvement in Metallic Boxes, of which the following is a specification.

The invention relates to sheet metal knock-down boxes, and the object of the invention is to provide a box which may be easily and quickly assembled, and the several members thereof stiffly and securely interlocked, with the corners strongly reinforced, and in which, when the box is packed and the cover applied, the contents are securely protected and access thereto impossible except by destructive mutilation of one or more of the box members.

The invention consists in certain novel features and details of construction and arrangement by which the above objects are attained, to be hereinafter described and claimed.

The accompanying drawings form a part of this specification and show two forms of the invention.

Figure 1 is a side elevation of the improved box.

Fig. 2 is an end view of the same, partly in vertical section.

Fig. 3 is a corresponding plan view, partly in horizontal section.

Fig. 4 is an interior perspective view of one of the corners at the junction of an end, side, and the bottom, before the application of the cover.

Fig. 5 is a plan view of such corner, on a larger scale.

Fig. 6 is a corresponding view before the application of the corner locking member.

Fig. 7 is a plan or end view of the corner locking member alone.

Fig. 8 is a vertical section showing the engagement of the cover with an end or side.

Fig. 9 is a perspective view of a corner of such cover.

Fig. 10 is a horizontal section of a locked corner corresponding to Fig. 5 but showing a modified form of lock.

Fig. 11 is a similar view showing the junction of an end and side of such modified form, before the insertion of the locking member.

Fig. 12 is a section through such modified locking member.

Similar letters of reference indicate like parts in all the figures.

The box is rectangular and comprises the side members A A and end members B B, a bottom member C and a cover member D, all preferably of sheet metal and each a single independent piece. The bottom C and cover D may be, and are shown as, in all respects alike and either may serve in either capacity.

In the form shown in Figs. 2 to 7 inclusive, the adjacent interior edges of the sides and ends at the vertical corners of the box are each bent upon itself twice, as at F G to form a double fold with a hook-shaped recess f g in each when seen in plan view as in Fig. 6, adapted to receive a similarly shaped locking member E having each edge folded or bent as at K, to match to the recesses f g. The locking member is of the same height as the side and end members and is engaged by inserting its end into such recesses and forcing it down into the position shown in Fig. 4. Each corner is similarly joined thus forming an open rectangle ready to receive a bottom and cover. The body of the locking member extends diagonally across the corner, and with its folds and those of the end and side members reinforces the corner and insures its strength and stiffness.

On the upper and lower margins of each side and end member A and B is a wing H bent inwardly to project at a slight angle from the inner face of such side or end, and the bottom C and cover D are each provided with corresponding angular flanges J each flange having an outwardly projecting angular lip J¹. The wings H and flanges J extend nearly to the corners, the spaces thus provided being occupied by the locking members E. The bottom C is applied to the open rectangle by forcing its flanges J inwardly in opposition to the spring force offered by such flanges and by the wings H, until the lips J¹ pass and snap over and thus engage the wings, as shown in Fig. 4, and secure the bottom in place. A marginal bead J² forming the edges of the bottom at the junction of the flanges J therewith, applies closely to the adjacent edges of the end and side members and affords a smoothly rounded finish.

The cover D is in all respects similar to

the bottom and is applied in the same manner; the lips J^1 of its flanges engage the wings H on the upper edges of the end and side members, as shown in Fig. 8.

5 The contents must be packed in the box before the cover is applied, and when the cover is applied, forced down and engaged, the box is effectually sealed and the contents cannot be reached without destroying or permanently mutilating the box.

10 Figs. 10, 11 and 12, show a form of corner joint in which the adjacent edges of the side member A^1 and end member B^1 are each bent inwardly to produce a single fold

15 as at F^1 G^1 , and the locking member E^1 has its edges bent to produce single flanges as at K^1 to match to and engage with the folds F^1 G^1 as shown in Fig. 10. The assembling and application of the bottom and

20 cover is the same as in the form first described. This modified form of joint is simpler and will serve successfully but is not so secure as the preferred joint first described.

25 The sides, ends, bottoms and covers may be packed and shipped in the knocked down flat condition and assembled as required.

It will be noted that all the members are of single pieces of sheet metal, adapted to 30 be produced by suitable cutting and forming dies of analogous tools.

I claim:—

1. In a box of the character set forth, side and end members having their adjacent ver-

tical edges bent inwardly with their bends 35 abutting forming folds at the interior corners of the box with the terminals of said side and end members disposed at right angles to each other, removable locking members disposed interiorly of the box at 40 the corners thereof, each having its edges bent to match said folds with their free edges disposed in said bends, and a bottom and a cover each having means co-operating and interlocking with means on 45 the side and end members.

2. In a box of the character set forth, side and end members having their adjacent vertical edges bent inwardly to form opposite folds at the interior corners of such box, inwardly bent angularly projecting wings on the upper and lower margins of said members, a locking member for each corner, each comprising a single piece of sheet metal having its edges bent to match to and engage 50 said folds, and to extend diagonally across such corner, and a bottom and a cover, each having an inwardly bent angularly projecting flange on each of its edges, and an outwardly projecting lip on each of 55 said flanges, said lips adapted to engage said wings and hold said bottom and cover in locked engagement with said side and end members.

In testimony that I claim the invention 60 above set forth I affix my signature.

JOHN R. PEARSON.
